UNITED STATES PATENT OFFICE.

DANIEL W. SHIEK, OF CHICAGO, ILLINOIS.

STAIR-CARPET RETAINER.

1,106,320.

Specification of Letters Patent.

Patented Aug. 4, 1914.

Application filed August 19, 1912. Serial No. 715,798.

To all whom it may concern:

Be it known that I, DANIEL W. SHIEK, a citizen of the United States, residing at Chicago, in the county of Cook and State 5 of Illinois, have invented certain new and useful Improvements in Stair-Carpet Retainers, of which the following is a description.

My invention belongs to that general 10 class of devices adapted for securing carpets in position, and relates particularly to a stair carpet retainer or fastening.

Stair carpets, as a rule, are more or less difficult to lay and secure in position, or to 15 take up, the most common way of securing them being by the use of tacks. If the stairs are of wood the tacks mar the same, and if the carpet is relaid very many times, the treads are covered with tack holes. In 20 the case of marble, stone, or like stairs, if tacks or similar fasteners are used, suitable strips or plugs must be inserted or inlaid to afford attachment for the tacks. This is extremely expensive, and often very un- 25 sightly and undesirable. When the stair carpet so secured is removed, considerable time and care is required in order not to mar or injure the stairs or injure the carpet. The device herein described is designed to 30 overcome all of the disadvantages arising from the use of tacks or other fasteners.

The invention has among its objects the production of a device of the kind described that is simple, convenient, efficient, attractive, and satisfactory, and which may be manufactured at comparatively small cost.

Among its other objects is the production of a fastener or retainer, applicable on stairs of wood, marble, or other material, and that 40 may be easily applied or removed, and without defacing or injuring the stairs or carpet.

To this end my invention consists in the novel construction, arrangement and combination of parts herein shown and described, and more particularly pointed out in the claims.

In the drawings, wherein like reference characters indicate like or corresponding parts, Figure 1 is a front elevation of several stairs and carpet, showing one form of the device applied thereto. Fig. 2 is a sectional view of the stairs and an end elevation of the device and carpet. Fig. 3 is a

perspective view of one of the retainers shown in Figs. 1 and 2. Fig. 4 is an enlarged view of a portion of one of the retainers, showing one form of construction. Fig. 5 is a similar view showing another construction. Fig. 6 is a similar view showing another construction. Fig. 7 is a similar view of a modified arrangement. Fig. 8 is a similar view of a portion of a retainer used with a pad. Fig. 9 is a front elevation of several stairs and carpet, showing a modified retainer. Fig. 10 is a sectional view of the stairs and end elevation of the retainer and carpet. Figs. 11 and 12 are similar views of still another construction. Fig. 13 is a front elevation of a portion of a modified device. Fig. 14 is a perspective view of a portion of a stair and carpet, showing an additional attachment, and Fig. 15 is a front elevation of a portion of another modified construction and attachment.

The present invention broadly consists of a member adapted to lie in front of the carpet, in the corner, at the juncture of the tread and riser, to maintain the carpet in position at that point. The same is provided with suitable means for contacting or engaging with the stair tread and with the next higher tread.

In the drawings I have shown several forms of the invention, all of which operate 85 in substantially the same manner, and with the same results, and are more or less similar in construction.

In all the figures, 1 represents the stair tread of wood, marble, stone, iron or other 90 material, and 2 the riser, the stair carpet 3 extending over the stairs in the usual manner. The retainer shown in Figs. 1, 2 and 3, there being one for each step or tread, consists of a bar or rod 4 extended at each 95 end as at 5, 6, the bar being essentially substantially resilient or yielding. In securing the carpet in position, the part 4 is placed proximate the juncture of the tread and riser at substantially the point where 100 the tacks are usually employed. The ends 5 are extended back of the carpet and sprung into position with their ends 6 in contact or in engagement with the underside of the next higher adjacent tread.

The part 4, or that is, what may be

termed the bar, is preferably provided with suitable means for engagement with its tread. In Figs. 4, 5, 6 and 7, I show several methods of securing the bar 4 in position, and preventing transverse horizontal displacement of the same relative the tread. In Figs. 1, 2, 3 and 4 the bar 4 is shown with the needle point 7, or that is a pointed lug at each end that will engage or indent the tread 1, as at 8. The indentation 8 may be formed either by the pressure of the lug or pin 7, or the tread may be suitably countersunk before the retainer is placed in position. This style of lug is suitable for use on wooden stairs.

In Fig. 5, the bar, which to prevent confusion, I have designated as 4', may be provided with a foot 7' at each side of the carpet, which foot is preferably constructed of rubber, or other equivalent material, so that the stair tread 1 is frictionally engaged. In Fig. 6 the bar 4² is provided with a blunt lug 7², adapted to fit into a recess 8² in the tread. This construction is particularly suitable for marble, or similar stairs. In Fig. 7 the bar 4³ is made without lugs, a lug or pin 9 being secured to the tread on each side of the carpet. This lug or pin 9 may be of any suitable form, that shown being a screw provided with a suitable head. Any of these forms may be employed, the same depending upon the nature of the stairway and the preference of the user of the device. If the retainer is made of considerable stiffness; the friction of the carpet upon the stair tread will, in some cases, make the use of lugs, or their equivalents, on the bar or stair, unnecessary. This is particularly true where a pad is used under the carpet, which substantially wedges the device in place. (See Fig. 8). In this case, if desired, the pad 30 may be secured to the step by adhesive or other fasteners. Inasmuch as there is no transverse strain upon the part of the retainer in engagement with the higher tread, it is unnecessary to provide any engaging means at that point. However, it should be understood that the ends 6, or their equivalents, may be provided with lugs similar to those shown in any of the Figs. 4, 5, 6 or 7, which may directly or frictionally engage the tread.

A slightly different construction is shown in Figs. 9 and 10, in which 10 represents a bar provided with ends 12 adapted to engage the tread at 13, and with resilient ends 14, to which may be secured parts or bars 15 for engagement with the next higher tread. As shown, these bars 15 are pivotally secured at 16 to the parts 14. In use this device serves the same purpose as that previously described, and may be arranged for engagement with the treads in any of the ways previously shown or described.

In Figs. 11 and 12 the retainer 17 is ex-

tended as at 18, 19, for engagement with the next higher tread. This device is substantially the same as that shown in Figs. 1, 2 and 3, except that it engages with the higher tread at each side of the carpet instead of in back.

In Fig. 13 I show a portion of a bar, which may be similar to any of those previously described, as regards form and contact with the treads. In this case, however, the bar 20 is shown provided with needle points, or pointed lugs 22, which are adapted to pierce the carpet or the carpet and pad. The bar is shown provided with lugs 21, which, as mentioned, may be similar to any of those previously described.

In Fig. 14, an additional element, namely, an angle bar 23, is shown. The retainer shown is similar to that shown in Figs. 1, 2 and 3, but may, however, be similar to either of those shown in Figs. 9 and 11, or their equivalent. While the angle 23 is not shown with lugs or pins for engaging the carpet, it may be provided with pins substantially similar to those shown in Fig. 13 on the bar 20.

In Fig. 15 an angle bar 24, substantially similar to that before described, is shown; in this case, however, a slightly different form of retainer or resilient bar is shown. In this case the bar 25 engages the upper tread, while its ends 26 and shoulder 27 engage the lower tread, the same either passing in front of or through the bar 24, which retains the carpet in position.

It will be seen that any of the retainers described may be very readily positioned or removed in laying or taking up the carpet, and by their use the stairs are not defaced or injured in any way. The retainers are not unsightly and may be made as attractive in finishing or by ornamentation as preferred or desired.

Having thus described my invention, it is obvious that various immaterial modifications may be made in the same without departing from the spirit of my invention, hence I do not wish to be understood as limiting myself to the exact form, construction, arrangement or combination of parts herein shown and described, or uses mentioned.

What I claim as new and desire to secure by Letters Patent is:—

1. A device of the kind described, comprising a bar arranged at the juncture of the tread and riser, engaging means between said bar and the stair tread, and resilient means at each end coöperating with the next higher tread for resiliently maintaining said bar in operative relation to said first mentioned tread.

2. In a device of the kind described, in combination with a bar, provided with means at each end for engagement with a stair tread, and with means at each end co-

operating with an adjacent tread for resiliently maintaining said bar in engagement with said first mentioned tread.

3. A device of the kind described, consisting of a bar provided with a lug at each end with a resiliently extending part formed integrally with the bar on each end on the side opposite said lug.

In testimony whereof, I have hereunto signed my name in the presence of two subscribing witnesses.

DANIEL W. SHIEK.
